UNITED STATES PATENT OFFICE.

SAMUEL B. MORRELL, OF GLOVERSVILLE, NEW YORK.

DESIGN FOR A CUFF FOR A GAUNTLET-GLOVE.

52,920.

Specification for Design.

Patented Jan. 28, 1919.

Application filed April 25, 1918. Serial No. 230,810. Term of patent 14 years.

To all whom it may concern:

Be it known that I, SAMUEL B. MORRELL, a citizen of the United States, residing at Gloversville, in the county of Fulton and State of New York, have invented a new, original, and ornamental Design for a Cuff for a Gauntlet-Glove, of which the following is a specification, reference being had to the accompanying drawing, in which—

Figure 1 is a perspective view of a cuff for a gauntlet glove, the glove proper being shown in dotted lines and not constituting a part of the invention.

Fig. 2 is a plan view of the cuff alone in its unfolded position.

I claim:—

The design for a cuff for a gauntlet glove substantially as shown.

In testimony, that I claim the foregoing as my own, I have hereto affixed my signature in the presence of two witnesses.

SAMUEL B. MORRELL.

Witnesses:

WILLIAM A. MACDONALD,
JANE M. PEELS.
